MEANS FOR SUPPORTING VERTICAL GUIDES AND OTHER MEMBERS

Filed July 7, 1932

UNITED STATES PATENT OFFICE

1,957,630

MEANS FOR SUPPORTING VERTICAL
GUIDES AND OTHER MEMBERSFrederick Merrill Chandler, Union City, and
Herman Carl Werner, Montclair, N. J.

Application July 7, 1932, Serial No. 621,144

8 Claims. (Cl. 187—95)

This invention has been devised with the object of assuring more safety and more comfort in the operation of elevator cars and effecting a substantial saving in the erection and servicing costs. In its preferred embodiment the invention is a device for attaching elevator guide rails to their supports, particularly adaptable in the taller buildings and on higher speed elevators.

10 The present practice is to attach elevator guide rails to the building supports by means of solid brackets, the brackets being bolted or riveted to the building structure, the guides being bolted or clipped to the bracket. Any variation that 15 takes place in the walls or members of the building that support the guide rails and brackets, such as the shifting of supports due to compression settlement, temperature, etc., is directly conveyed to the guide rails, forcing the guide rails 20 out of alignment, as the guide rail does not compress or have the same change caused by compression, temperatures, etc., as the building, but takes the least line of resistance, which is to buckle or bend, causing the elevator car to sway 25 uncomfortably to the passengers, causing excessive wear and tear on the equipment, and may reach a very dangerous condition when the guides may be forced out of alignment to such an extent that the elevator car safety device will no 30 longer operate properly on the guides, and the elevator car guide shoes or slides may leave the guide rail entirely and the car strike various projections in the elevator hatch, causing a serious accident.

35 In order to avoid the dangers as outlined and to keep the car operating fairly smooth and comfortable to the passenger, the practice at present is to realign the guide rails as required, which is a very costly operation, and the elevator is 40 out of service during the realignment period.

This invention eliminates the cost of realigning the guides, and only requires periodical inspecting during the period that the building compresses and if adjustments are necessary, only a 45 few minutes are required to each device. This invention will maintain the guides as they were initially aligned, as they allow the building supports to shift and do not apply this movement to the guides, and yet the guides are supported 50 by the building through the means of this invention, and will maintain safe and comfortable operation of the elevator car.

One form of the invention is illustrated in the accompanying drawing, in which Figure 1 is a 55 front elevation of the combination, Figure 2 is

a top plan view of the combination, Figure 3 is a side elevation of the combination, Figure 4 is a front elevation of the members fixed to the building structure or support that is provided for the purpose, Figure 5 is a side elevation of the 60 singular, Figure 6 is a bottom plan view of the combination, Figure 7 is a cross-sectional view taken horizontally on the line 27—27, Figure 1.

The desired accomplishment of maintaining elevator guide rails vertically in alignment, supported at approximately twelve foot intervals by the building structure, the supports varying their horizontal position as well as the distance between supports due primarily to the compression of the building, which is an action that takes 65 place in every building, particularly in the taller buildings where the compression may reach as much as one-eighth inch to every fifteen feet of building height, is accomplished as follows,— when used as a combination Figures 1, 2, 3, 70 75 (guide pin 23, spring 24, compression sleeve 29 and yoke 28 being omitted) a supporting base 1, which by means of bolts through holes 26 is fastened to members of the building structure or walls in the elevator shaft 3 a connecting link 80 85 pivoted on 1 through means of pin 2 so as to pivot vertically 4 a guiding casting or assembly attached to connecting link 3 by means of tie plates 6 fitted into slot on 3 so as to allow rotation of 4 on 3 antifriction washer 5 between 3 85 and 4, a sliding member 7 is free to slide within 4 corrugated rollers 8 allow slide 7 to slide in the up direction but arrest any downward movement of slide 7 by wedging between the wedge shaped recess in 4 and the slide 7 a common type 90 of elevator guide rail 9 attached to slide 7 by means of clips 11 and bolts 10 shims 12 are used to pack out the guide rail to the required distance where necessary 13 a pulley revolving on pin 14 attached to base 1 screw rods 15 screwed through 95 upper section of base 1 actuate compressing block 16 which in turn applies the necessary tension on spring 18 to exert the required pull on chain 19 through its tension on the shoulder of sliding pin 17 which is connected to the chain by means of 100 pin 20 the chain 19 runs over the pulley 13 and the other end is attached to slide 7 by means of pin 21 sufficient tension is applied to spring 18 so as to exert the necessary lift on slide 7 through the chain 19 over the pulley 13 to lift the slide 7 105 plus the weight of the elevator guide rail 9 from this point of support to the next point of support and so on throughout the entire length of the elevator guide. This combination compensates for any uneven movement of the building structure 110

- to which it is attached vertically to the horizontal as well as downward, supporting and maintaining the elevator guide in alignment. When used to compensate for even vertical movement 5 of building supports (the parts illustrated in Figure 4 are entirely omitted), (yoke 28, compression sleeve 29, guide pin 23 and spring 24 are added).
- Guiding casting 4 is bolted to the building 10 structure or supports provided for the purpose through holes 25, slide 7 guided within 4 rail 9 attached to slide 7 by means of clips 11 and bolts 10 and packed out to the required distance by shims 12, slide 7 is under tension in the upward 15 direction by the compression of spring 24 and is held in position on slide 7 by guide pin 23 tension is applied to spring 24 by means of compression screw 22 by means of sleeve 29, the tension on spring 24 is adjusted so as to lift the 20 weight of slide 7 plus the weight of the rail 9 from this point of support to the next point of support and so on throughout the entire length of the elevator guide. Corrugated rollers 8 allow 25 upward movement of slide 7 but arrest any downward movement by wedging themselves between slide 7 and the wedge shaped recess in 4. Through this means the elevator guide rail is held in its desired position with the necessary support to hold the stresses and strains that may 30 be applied to the elevator guide such as when the fully loaded elevator car safety operates on the guide.
- What we claim as our invention and desire Letters Patent,—
- 35 1. Means for connecting an elongated vertical member at a plurality of points, spaced along its length, to a fixed object, comprising at each of said points a supporting element mounted on said fixed object, a holding element fixed to said vertical member, a pivotal connection between said supporting and fixed elements to permit one to rock with respect to the other on two horizontal axes at right angles to each other and permitting relative bodily movement between them only 40 in a vertical direction, and means for yieldingly opposing such relative bodily movement.
2. Means for connecting an elongated vertical member at a plurality of points, spaced along its length, to a fixed object, comprising at each of 45 said points a supporting element mounted on said fixed object, a holding element fixed to said vertical member, means for connecting said supporting element with said holding element to permit relative bodily movement between said elements only in a vertical direction, and a yielding connection between said elements for locally supporting the vertical member against gravity.
3. Means for connecting an elongated vertical member at a plurality of points, spaced along its 50 length, to a fixed object, comprising at each of said points a supporting element mounted on said fixed object, a holding element fixed to said vertical member, means for connecting said supporting element with said holding element to permit relative bodily movement between said elements only in a vertical direction, means for arresting the downward movement of the holding element with respect to the supporting element, and a yielding connection between said ele- 55
- ments for locally supporting the vertical member against gravity.
4. Means for connecting an elongated vertical member at a plurality of points, spaced along its length, to a fixed object, comprising at each of said points a supporting bracket mounted on said fixed object, a slide fixed to said vertical member and slidably arranged in said supporting bracket to permit relative bodily movement between said slide and bracket only in a vertical direction, and a spring connection between said bracket and said slide for locally supporting the vertical member against gravity upon said bracket. 60
5. Means for connecting an elongated vertical member at a plurality of points, spaced along its length, to a fixed object, comprising at each of said points a supporting bracket mounted on said fixed object, a slide fixed to said vertical member and slidably arranged in said supporting bracket to permit relative bodily movement between said slide and bracket only in a vertical direction, a spring connection between said bracket and said slide for locally supporting the vertical member upon said bracket, and means for adjusting the force of said spring. 65
6. Means for connecting an elongated vertical member at a plurality of points, spaced along its length, to a fixed object, comprising at each of said points a supporting bracket mounted on said fixed object, a slide fixed to said vertical member and slidably arranged in said supporting bracket to permit relative bodily movement between said slide and bracket only in a vertical direction, means for limiting the downward movement of said slide with respect to said bracket, and a spring connection between said bracket and said slide for locally supporting the vertical member upon said bracket. 70
7. Means for connecting an elongated vertical member at a plurality of points, spaced along its length, to a fixed object, comprising at each of said points a base plate fastened to said fixed object, a supporting bracket pivotally attached to said plate to rock on two horizontal axes at right angles to each other, a slide fixed to said vertical member and slidably arranged in said bracket to permit relative bodily movement between said slide and bracket only in a vertical direction, and a yielding support for said slide for locally supporting the vertical member upon said plate. 75
8. Means for connecting an elongated vertical member at a plurality of points, spaced along its length, to a fixed object, comprising at each of said points a base plate fastened to said fixed object, a supporting bracket pivotally attached to said plate to rock on two horizontal axes at right angles to each other, a slide fixed to said vertical member and slidably arranged in said bracket to permit relative bodily movement between said slide and bracket only in a vertical direction, a spring connection between said slide and said base plate for locally supporting the vertical member upon said plate, means for limiting the downward movement of said slide with respect to said bracket, and means for adjusting the force of said spring. 80
